UNITED STATES PATENT OFFICE.

CHARLES V. FOULDS, OF BERKELEY, CALIFORNIA, ASSIGNOR TO THE PELTON WATER WHEEL CO., OF SAN FRANCISCO, CALIFORNIA, A CORPORATION OF CALIFORNIA.

SLEEVE ASSEMBLY FOR VALVE STEMS, PISTON RODS, SPINDLES, PLUNGERS, AND THE LIKE.

Application filed February 12, 1927. Serial No. 167,625.

Valve stems, piston rods, spindles and plungers at their point of passage through packing glands or other sealing devices and into the atmosphere for exterior connection 5 with operating means or other elements are subject to corrosive action. This corrosion of the stem, valve or spindle has been generally overcome by applying a sleeve, of what is commonly termed non-corrosive metal, to 10 the stem, shaft or spindle.

Metal having non-corrosive properties does not generally possess the strength and physical qualities for carrying the stresses necessary in valve stem, piston rod, spindle or 15 plunger operation, thus in overcoming the corroding and pitting of the stem shaft or plunger, a material capable of carrying the stresses and strains of operation of a valve stem, shaft or plunger operation is employed 20 as an operating body and the same is surrounded by a relatively thin sleeve of non-corrosive and non-pitting material which reciprocates therewith.

While this construction, as at present 25 mounted, overcomes the corroding and pitting of the main operating body, it has serious objections when the sleeve operates within a fluid pressure chamber and extends outwardly therefrom into the atmosphere, or in- 30 to a zone of lower pressure than that of the main pressure chamber.

Through imperfection in the non-corrosive material or defects in the joint seal connection 35 between the non-corrosive material and the main operating body which may be a valve stem, piston rod, spindle or plunger, the fluid under pressure in the pressure chamber, or chamber of highest pressure, where two or more chambers are employed, often 40 finds its way beneath the inner surface of the sleeve, follows along the same to a point where the sleeve is operating in a zone of lower pressure than that of the pressure chamber, and causes a distortion or bulging 45 outwardly of the relatively thin sleeve, the latter blocking or precluding further movement of the valve stem, piston rod, spindle or plunger, as the case may be, in either direction.

50 My present invention relates to an improved sleeve assembly for valve stems, piston rods, spindles, plungers and the like, whereby the accumulation of internal pressure beneath the sleeve is overcome, and

whereby the liability of the distortion of the 55 sleeve is eliminated, removing the liability of the interruption of operation of mechanism from this cause.

The objects of the present invention, amongst others, are to enable, with entire 60 safety, the use of a non-corrosive sleeve of thinner wall dimensions than has heretofore been possible; provide a construction wherein the outside diameter of the main valve stem is maintained at its maximum for any given 65 outside diameter of the assembly; one wherein an outlet is provided for any fluid which may find its way between the surface of the stem and the inner wall of the sleeve; to provide a structure wherein the sleeve is sealed to 70 its parent part at a point within the pressure zone within which the part is operating to preclude the entrance of fluid under pressure beneath the sleeve surface; and to provide a structure wherein a vent is provided in the 75 sleeve for releasing to atmosphere or into a chamber of lower pressure, fluid under pressure which may find its way beneath the surface of the shell.

With the above mentioned and other objects in view, the invention consists in the novel construction and combination of parts hereinafter described, illustrated in the accompanying drawings and pointed out in the claims hereto appended; it being understood 80 that various changes in the form, proportion, size and minor details of construction within the scope of the claims may be resorted to without departing from the spirit or sacrificing any of the advantages of the invention. 85

In the drawings, forming a part of the application—

Fig. 1 is a view in vertical section of one embodiment of my invention as applied to the 90 stem of a valve.

Fig. 2 is a broken vertical section of a valve stem with one embodiment of my invention 95 illustrated in connection therewith.

Fig. 3 is a transverse sectional view on line 3—3 of Fig. 2.

Fig. 4 is a detailed sectional view of a modified construction of the upper end of a tailrod.

Fig. 5 is a transverse section taken on line 5—5 of Fig. 2.

In the drawings, disclosing one application 100 of the invention, and wherein like characters of reference designate corresponding parts—1 indicates a valve body, the fluid passage 2

therethrough being controlled by a gate valve 3, of any suitable structure.

From the valve 3 extends a stem 4 to the end of which is attached a tailrod 5. To the 5 stem 4 is secured a piston 6 operating within a cylinder 7, through the end wall of which reciprocates the end of the tailrod 5.

Operating pressure is supplied to the cylinder 7 at opposite sides of the piston 6 to open 10 and close the valve 3, by any suitable mechanism, conventionally illustrated at 8.

As any suitable mechanism for alternately directing operating pressure against opposite faces of the piston 6, and well known to those skilled in this art, may be employed, and as the same does not form any part of the present invention, its detailed description is not thought to be necessary.

The valve stem reciprocates through packing glands 9 in the walls 10, separating the valve body 1 and cylinder 7, and the tailrod likewise reciprocates through a gland 11 in the wall of the cylinder 7.

The surface of the stem 4, preferably between 25 its point of attachment to the gate valve 3 and its point of mounting the piston 6 is longitudinally grooved at 12, the grooves at their upper ends being connected through ducts 13 drilled radially into the stem and intersecting 30 at the base of a bore 14, drilled centrally of said stem, and extending axially through that portion of the stem mounting the piston 6.

A sleeve 15 of relatively thin metal, of the 35 type commonly referred to as non-corrodible, tightly embraces the stem 4, its ends being united to the stem by welding or other methods of attachment 16, to afford a leak-proof joint between the sleeve and stem body.

The tailrod 5 is threadably tapped into the 40 end of the stem 4, and for a short distance is axially drilled at 17 to afford a bore for registering with the bore 14. Like the main portion of the stem 4, the surface of the tailrod 45 is longitudinally grooved at 12, the grooves at their lower ends being interconnected by a circumferential channel 19 cut in the surface of the tailrod, and at their opposite ends connecting with lateral ducts 20 opening 50 to the atmosphere.

Snugly embracing the grooved portion of the tailrod is a relatively thin shell 21 of what is commonly termed non-corrosive material, the shell and tailrod being substantially 55 united at 22 by a leak-proof joint of any suitable type.

It will be observed that the portion of the 60 valve stem and that portion of the tailrod reciprocating in stuffing boxes or glands and extending into chambers or zones differing in pressure from that in which the main portions of the stem or tailrod operate, are provided with a sleeve of non-corrosive material, and beneath said sleeve are provided with 65 vents or passages through which any fluid

finding its way beneath the shell is conveyed to a point of discharge, without permitting the fluid accumulating under pressure and distorting the non-corrosive sleeve.

While the embodiment and application of the invention is illustrated and described as applied to a valve stem, it is to be understood that the invention is adaptable for use with piston rods, spindles, plungers for pumps, compressors and the like, and, in fact, with any form of power transmitting or guide member, the surface of which it is desired to protect against corrosion or pitting and which member is adapted to reciprocate in zones of unequal pressure, or in a single pressure zone and extend into or communicate with atmospheric pressure.

I claim:—

1. In combination with a pressure chamber, a rod therein and extending therefrom through the chamber wall, a shell tightly embracing the rod and affording a protecting cover therefor, portions of opposing surfaces of said rod and shell lying in spaced relation, affording a passage therebetween extending 90 endwise of the rod and other portions of said rod and shell lying in supporting contact to prevent the collapsing of the shell, means for providing a fluid tight joint connection between the rod and shell, said passage being 95 vented at a point without said pressure chamber.

2. In combination with a pressure chamber, a movable rod extending thereinto and operating through said chamber wall, a shell 100 tightly embracing the rod and forming a protecting cover therefor, said rod beneath said shell being provided with a longitudinal groove, and means for providing a fluid tight joint connection between the rod and shell 105 within the chamber, said groove being vented at a point without said pressure chamber.

3. In combination with a pressure chamber, a movable metal rod extending thereinto and operating through said chamber wall, a relatively thin shell of a metal differing 110 from that of the rod tightly embracing the rod and forming a protecting cover therefor, portions of said rod and shell lying in spaced relation affording passages therebetween and other portions of said rod and shell at points throughout their length lying in supporting contact to prevent the collapsing of the shell, means for providing a fluid tight joint connection between the rod and shell within the chamber, said passage being 115 vented exteriorly of the chamber.

4. In combination with a pressure chamber, a movable metal rod extending thereinto and operating through said chamber wall, a 125 relatively thin shell of a metal differing from that of the rod, tightly embracing the rod and forming a protecting cover therefor, the surface of said rod being provided with a plurality of lineally disposed grooves and fur- 130

ther provided with one or more circumferential grooves connecting the lineal grooves, said rod being further provided with a central base and radial ducts connecting the bore with the circumferential grooves, said grooves, bore and ducts affording a relief passage between the rod and shell, said bore affording a vent opening for the passage exteriorly of the pressure chamber, and means for providing a fluid tight joint connection between the rod and shell within the chamber.

5. In combination with a pressure chamber, a rod therein and extending exteriorly thereof, a shell embracing the rod and affording a protecting cover therefor, portions of said rod and shell lying in spaced relation affording a passage therebetween extending endwise of the rod and other portions of said rod and shell at points throughout their 15 length lying in supporting contact to prevent the collapsing of the shell, a gland with which the surface of said shell contacts, and means for providing a fluid tight joint con-

nexion between the shell and rod at a point within the chamber.

6. In combination with a pressure chamber, a rod therein and extending exteriorly thereof, a shell embracing the rod and affording a protecting cover therefor, portions of said rod and shell lying in spaced relation affording a passage therebetween extending endwise of the rod, other portions of said rod and shell at points throughout their length lying in supporting contact to prevent the collapsing of the shell, said passage being vented exteriorly of the chamber, a gland with which the surface of said shell contacts, and means for securing the rod and shell together at a point within the chamber, said securing means precluding the entrance of pressure from the chamber to the space between the rod and shell at their point of attachment.

In testimony whereof I have signed my name to this specification.

CHARLES V. FOULDS.
